UNITED STATES PATENT OFFICE.

HOMER LAUGHLIN, OF EAST LIVERPOOL, OHIO.

DESIGN FOR THE ORNAMENTATION OF DISHES.

SPECIFICATION forming part of Design No. 20,968, dated July 28, 1891.

Application filed March 4, 1891. Serial No. 383,808. Term of patent 7 years.

To all whom it may concern:

Be it known that I, HOMER LAUGHLIN, a citizen of the United States, residing at East Liverpool, in the county of Columbiana and State of Ohio, have invented and produced a new and original Design for the Ornamentation of Dishes, of which the following is a specification, reference being had to the accompanying engravings, forming part thereof.

10 In the accompanying illustrations, Figure 1 is a view of a soup-tureen and platter. Fig. 2 is a view of a tea-pot. Fig. 3 is a view of a cup, and Fig. 4 is a cake-plate.

15 A is a handle, made in the form of a tusk or horn. All of the articles above enumerated are thus provided, and this horn or tusk

constitutes a leading feature of my design. Still another feature consists in the representation of the sprays of leaves and flowers B, arranged in artistic clusters on the surfaces 20 of the several articles, as shown in the accompanying illustrations, and preferably so as to form a shield-shaped division C.

Having fully described my design, what I claim as new, and desire to secure by Letters 25 Patent, is—

The design for the ornamentation of dishes herein shown and described.

HOMER LAUGHLIN.
